DESIGN FOR AN AUTOMOBILE RADIO REMOTE CONTROL

Albert G. Redmond, Flint, Mich., assignor to
Noblitt-Sparks Industries, Inc., Columbus, Ind.,
a corporation of Indiana

Application February 11, 1935, Serial No. 55,331

Term of patent 7 years

To all whom it may concern:

Be it known that I, Albert G. Redmond, a citizen of the United States, residing at Flint, in the county of Genesee, and State of Michigan, have invented a new, original, and ornamental Design for an Automobile Radio Remote Control, of which the following is a specification, reference being had to the accompanying drawing.

In the accompanying drawing:

Figure 1 is a perspective view of the automo-

bile radio remote control showing my new design, and

Figure 2 is a top plan view thereof.

I claim:

The ornamental design for an automobile radio remote control, as shown.

In testimony whereof, I hereunto affix signature.

ALBERT G. REDMOND.
